US0D1003661S

(12) **United States Design Patent** (10) **Patent No.:** **US D1,003,661 S**
(45) **Date of Patent:** ** *Nov. 7, 2023

(54) **BEVERAGE CONTAINER WITH LID**

(71) Applicant: **BruMate, Inc.**, Dover, DE (US)

(72) Inventor: **Dylan M. Jacob**, Denver, CO (US)

(73) Assignee: **BruMate, Inc.**, Denver, CO (US)

(*) Notice: This patent is subject to a terminal disclaimer.

(**) Term: **15 Years**

(21) Appl. No.: **29/766,604**

(22) Filed: **Jan. 15, 2021**

(51) **LOC (14) Cl.** **07-01**

(52) **U.S. Cl.**

USPC **D7/510; D7/624.2**

(57) **CLAIM**

The ornamental design for a beverage container with lid, as shown and described.

DESCRIPTION

FIG. 1 is a front elevation view of a beverage container with lid showing my new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof; and,

FIG. 7 is a top perspective view thereof.

The even dash lines form parts of the article forming no part of the claim.

1 Claim, 7 Drawing Sheets
